UNITED STATES PATENT OFFICE.

P. A. DAILEY, OF NEW YORK, N. Y.

IMPROVED MIRROR.

Specification forming part of Letters Patent No. 56,723, dated July 31, 1866.

To all whom it may concern:

Be it known that I, P. A. DAILEY, of the city, county, and State of New York, have invented a new and Improved Mirror; and I do hereby declare that the following is a full, clear, and exact description thereof, which will enable others skilled in the art to make and use the same, reference being had to the accompanying drawing, forming part of this specification.

The nature of my invention consists in so constructing the frames to hand-mirrors of metal or other suitable material that they may be readily inserted or removed from the frames, together with the backs, and are also constructed in such a manner that there is no possibility of the frame springing or warping or in any manner getting out of order and breaking the glass.

The per cent. in loss by breakage by the springing and warping of the wooden frames to hand-mirrors has been so great that many dealers have refused to deal in them.

It more particularly consists in combining the rim or frame with the handle and back of the glass by means of a screw-thread made on the shank of the frame and corresponding screw-threads made in a socket at the lower end of the handle.

To enable others skilled in the art to make and use my invention, I will proceed to describe its construction.

The figure represents a top-plan view of my improved frame, with a portion of the handle broken out so as to show the screw-threads by which the handle is attached to the frame.

A represents the handle of my improved frame with a portion of the lower end removed

for the purpose of showing the manner by which it is attached to the frame. The said handle A may be made of any kind of fancy wood, hard rubber, or any other suitable material, the lower end of which may be provided with a ferrule for the purpose of giving strength and utility to the socket, the said socket being provided with a screw-thread, into which fits a corresponding screw-thread upon the shank of the frame, as seen at B.

C represents the frame, which is made of any of the metals suitable for such purposes, upon the inside of which is a groove of sufficient capacity to admit the glass D and back E.

Now, it will be understood that as the rim of the frame is bent round in a circle, ellipse, or other form, the ends that meet are formed into a sort of shank, upon which is cut a screw-thread, as represented at B, which fits into a corresponding thread in the end of the handle A, and by means of which the glass and back are firmly secured within the groove without any liability of the glass breaking by the warping of the frame.

Having thus described my invention, I claim as new and desire to secure by Letters Patent—

The combination of the handle A with the metal frame C, glass, and back, when constructed as and for the purposes and substantially as described.

The above specification of my invention signed by me this 12th day of June, 1866.

P. A. DAILEY.
